UNITED STATES PATENT OFFICE.

FREDERICK E. MUELLER, OF MOUNT VERNON, NEW YORK, ASSIGNOR TO THE NORMA COMPANY OF AMERICA, OF LONG ISLAND CITY, NEW YORK, A CORPORATION OF NEW YORK.

BALL-SIZING MACHINE.

1,366,130.

Specification of Letters Patent. Patented Jan. 18, 1921.

Application filed September 6, 1919. Serial No. 322,025.

To all whom it may concern:

Be it known that I, FREDERICK E. MUELLER, a citizen of Germany, and a resident of Mount Vernon, county of Westchester, State 5 of New York, have invented certain new and useful Improvements in Ball-Sizing Machines, of which the following is a specification.

The present invention relates to improvements in ball sizing machines, and particularly such machines for sizing balls of very fine precision such for instance as the anti-friction balls used in ball bearings.

It is an object of the invention to provide a machine of this character in which the balls may be fed singly and at uniform speed and which will preclude clogging of the balls in the machine. Other objects are to provide such a machine which may be made to accommodate different types of balls, that is, balls of substantially different diameters as distinguished from the balls of one type but of slightly different diameters, and therefore requiring sizing and to enable 25 the accurate adjustment of the sizing means.

With these and other objects in view, an embodiment of my invention is shown in the accompanying drawings and this embodiment will be hereinafter more fully described with reference thereto and the invention will be finally pointed out in the claims.

In the accompanying drawings,

Figure 1 is a side elevation of an embodiment of my invention shown by way of example herein;

Fig. 2 is an enlarged side elevation partly in section and with parts broken away;

Fig. 3 is an enlarged transverse vertical 40 sectional view taken along the line 3—3 of Fig. 2;

Fig. 4 is a front elevation, the supporting table and driving connections being removed;

Fig. 5 is a detail plan view with parts broken away of the sizing guideway;

Fig. 6 is a vertical sectional view taken along the line 6—6 of Fig. 5;

Fig. 7 is a longitudinal sectional view of 50 one of the socketed members for transferring the balls from one portion of the feeding mechanism through another; and

Fig. 8 is a plan view thereof.

Similar reference characters indicate corresponding parts throughout the several figures of the drawings.

Referring to the drawings, the embodiment of my invention shown therein comprises a raised ball receptacle 10 mounted upon a bearing member 11 engaging an annular recess 12 thereof, the said bearing member engaging an annular recess 13 provided in the enlarged upper head 14 of a standard 15, the elongated horizontal base 16 of which is secured by screws 17 to the table 18. The member 11 is held against movement by means of screws 19 extending upwardly through the head 14. The receptacle 10 is secured to the member 11 by means of screws 21.

Within the member 11 there is provided a transverse cylindrical bore 22, the upper surface of the said member being dished as at 23 and in communication with the said bore by an elongated opening 24, a diametrically opposed elongated outlet opening 25 being provided in the said member and communicating with the dished upper surface 26 of the head 14. Bearing caps 27 and 28 are screwed into the ends of the said bore 22 and having journaled therein a spindle 29, oil ducts 30 being provided in the said caps to enable lubrication of the spindle. Upon the projecting end of the spindle there is provided a pulley 31 adapted as will be presently more fully pointed out, to be driven from the transmission means.

A sleeve 32 having a plurality of radially disposed longitudinal grooves 33 therein, is mounted upon the spindle within the bore, 90 the said grooves adapted to register with the passages 24 and 25 and being of less width than the said passages.

Within the said grooves there are disposed bars 34 held in place by screws 35 and 95 provided with cut-out portions 36 forming a series of spaced pockets in longitudinal alignment and each adapted to receive a single ball. A screw 37 secures the sleeve 32 to the spindle. As the same is rotated 100 the balls disposed within the pockets are carried to the passage 25 and dropped into the dished portion 26 of the head 14 and thence into an offset passage 38 provided in

an enlargement 39 of the standard 15 beneath the head 14. Within the portion 39 there is provided a circular bearing opening 40 extending at one side into a reduced 5 hub portion 41 within which there is mounted a spindle 42, anti-friction bearings 43 and 44 being interposed between the said spindle and the hub, the said spindle being screw threaded at one end 42^a and provided with a disk 45 screwed thereon and locked in place by a nut 46, the periphery of the said disk being provided in spaced relation with sockets 47 into which the balls within the passage 38 are adapted to be 10 singly deposited and upon rotation of the said disk to drop periodically and singly into a tube 48 having its upper end supported in the lower portion of the enlargement 29 by means of a set screw 49, and in 15 communication with the opening 40.

A cover plate 50 threaded at its periphery, is engaged in a recess 51 annularly surrounding the opening 40. Upon the outer end of the spindle 42 there is provided a 25 stepped pulley 52 and also a pulley 53 smaller than the pulley 31 and connected thereto by a belt 54.

The stepped pulley 52 is connected by a belt 55 to a stepped pulley 56 mounted on a 30 shaft 57 journaled in bearing 58 provided in the table 18, the said shaft being driven by the speed reducing pulleys 59, 60, 61 and 62 and the belt connections 63 and 64 from the drive shaft 65, driven by means of a 35 pulley 66 and a belt 67 from a suitable motor or other source of power. A drawer 68 is provided beneath the table for containing balls in quantities to be sized.

The tube 48 is bent in a downwardly inclined direction as at 69, the balls rolling therefrom by gravity and at sufficiently timed periods to prevent their interfering with each other. A standard 70 adjustable as to height by means of a screw post 71 is 40 provided upon a support 72 in front of the standard 15 and having at its upper end a bearing 73 hingedly supporting a pair of bars 74 and 75, a pintle 76 connecting the said bars at their raised ends and passing 45 through the bearing to form a hinge, while their lower ends are spaced by a block 77 to which they are secured by screws 78 and 79, the said block being provided with a lug 80 engaging a groove 81 of a block 82 supporting the lower end of the said bars and 50 adapted to maintain their alignment.

Between the said bars there is provided a base member 83 secured thereto by means of bolts 84 passing upwardly through lugs 85 60 extending beneath the said bars, the said members being provided with upstanding sides 86 and 87 having a series of notches 88 formed along their upper edges, and partitions 89 disposed between the said sides 65 and forming a plurality of stepped pockets

90 having their bases inclined to depending outlet tubes 91 emptying into a corresponding number of drawers or receptacles 92 disposed upon a shelf 93 beneath the said tubes.

Plates 94 rest in inclined position at the forward ends of the said pockets upon the upper ends of the said partitions and are provided with projecting lugs 95 and 96 adapted to be adjustably engaged in the 75 notches 88 of the sides 86 and 87. Thus the extremities of the pockets may be adjusted or shifted in their position.

Upon the upper surface of the bars 74 and 75 there are respectively mounted a 80 series of plates 97 and 98 having their inwardly projecting ends beveled as at 99 and 100 to form a channel at the upper end of which the outlet end 69 of the tube 48 is disposed, the said plates being variably 85 spaced so that the balls will drop therethrough according to their particular size.

The plates 97 are provided with a pair of spaced transverse slots 101 and 101^a engaged by screws 102 and 103 to securely hold the 90 same to the bar 75, the plates being slightly spaced apart at their ends as at 104, and a slight play being provided between the screws and the slots to permit of an angular adjustment of the adjacent plates relatively 95 to each other and to the other line of the channel, so that a gradually diverging and accurately adjusted slot may be formed. The plates 98 are similarly provided with slots 105 and 106 and screws 107 and 108 100 and are slightly spaced at their ends as at 118.

The plates 97 are swivelly connected at one end as at 109 to a screw 110 engaging a nut 111, knurled at its periphery and fixed 105 against longitudinal movement between a pair of bars 112 and 113 through apertures 114 and 115 of which the screw extends, the said bars being spaced apart by sleeves 116 having connecting bolts 117 extending therethrough. The slight space 104 between the ends of the plates enables them to be angularly adjusted relatively to each other so that an accurate diverging slot may be formed, this slot either diverging continuously from its upper to its lower end or the same may consist of a plurality of diverging portions formed by the respective opposed plates or on the other hand the plates may have their edges disposed parallel to 115 each other, the plates at the upper end of the bars being closer together than the lower plates.

The opposed plates 97 and 98 are arranged relatively to the pockets 90, each pair of 125 plates terminating above the ends of the plates 94.

With my improvements a sizing machine is provided in which the balls will not clog in the feeding mechanism and will be fed 130

at regular intervals and at such timed periods as not to interfere with each other. The sizing slot may be accurately adjusted so that the balls may be sized with great precision.

I have illustrated and described a preferred and satisfactory embodiment of my invention but it is obvious that changes may be made therein within the spirit and scope 10 thereof as defined in the appended claims.

I claim:

1. In a sizing machine of the character described, means adapted to intermittently feed articles to be sized, an inclined runway 15 adapted to receive said articles and provided with a channel of gradually increasing width from its upper to its lower end, and means adapted to vary the width of said channel comprising a plurality of blocks 20 constituting one side of said runway, and means for individually adjusting said blocks transversely relatively to said channel, said means permitting adjustment of the blocks angularly with respect to each other.

2. In a sizing machine of the character described, means adapted to intermittently feed articles to be sized, an inclined runway adapted to receive said articles and provided with a channel of gradually increasing 25 width from its upper to its lower end, said runway comprising a pair of side supports, a plurality of blocks mounted on one of said supports and forming one side of said channel, means adapted to permit adjustment of 30 said blocks transversely of said channel, a plurality of blocks mounted on the other of said supports and forming the other side of said channel, and means adapted to adjust said blocks transversely of said channel, and 35 angularly with respect to each other.

3. In a sizing machine of the character described, means adapted to intermittently feed articles to be sized, an inclined runway adapted to receive said articles and provided 40 with a channel of gradually increasing width from its upper to its lower end, and means adapted to vary the width of said channel comprising a plurality of spaced blocks disposed end to end and constituting 45 one side of said runway, and means for individually adjusting said blocks trans-

versely relatively to said channel and angularly relatively to each other.

4. In a sizing machine of the character described, means adapted to intermittently feed articles to be sized, an inclined runway 55 adapted to receive said articles and provided with a channel of gradually increasing width from its upper to its lower end, and means adapted to vary the width of said channel comprising a plurality of blocks 60 . constituting one side of said runway, means for individually adjusting said blocks transversely relatively to said channel, and means swivelly connected to one end of said respective blocks adapted to adjust said blocks 65 angularly relatively to each other.

5. In a sizing machine of the character described, means adapted to intermittently feed articles to be sized, an inclined runway 70 adapted to receive said articles and provided with a channel of gradually increasing width from its upper to its lower end, means disposed beneath said channel having a plurality of spaced partitions constituting a 75 plurality of pockets adapted to receive different sized articles falling through said channel, outlet means for said respective pockets, and means adapted to adjust the end extremities of said pockets relatively to 80 said channel.

6. In a sizing machine of the character described, means adapted to intermittently feed articles to be sized, an inclined runway 85 adapted to receive said articles and provided with a channel of gradually increasing width from its upper to its lower end, means disposed beneath said channel having a plurality of spaced partitions constituting a plurality of pockets adapted to receive different sized articles falling through said 90 channel, outlet means for said respective pockets, and a plurality of guide plates disposed at the upper ends of said partitions, said plates being adjustable longitudinally 95 of said channel to adjust the extremities of said pockets relatively to said channel.

In testimony that I claim the foregoing as my invention, I have signed my name hereunder.

FREDERICK E. MUELLER.
